UNITED STATES PATENT OFFICE.

GEORGE CHRISTOPHER HERZ, OF NEW YORK, N. Y.

DESIGN FOR A SWITCH-BLADE.

SPECIFICATION forming part of Design No. 31,797, dated November 7, 1899.

Application filed October 7, 1899. Serial No. 732,972. Term of patent 3½ years.

To all whom it may concern:

Be it known that I, GEORGE CHRISTOPHER HERZ, a citizen of the United States, residing at New York, (Long Island City,) in the county of Queens and State of New York, have invented and produced a new and original Design for Switch-Blades; and I do declare the following to be a full, clear, and exact description of the same, reference being had to the accompanying sheet of drawings, forming a part thereof.

My invention relates to an original design for switch-blades for electric switches commonly known as "knife-switches."

The design is illustrated in the accompanying one sheet of drawings, in which—

Figure 1 is a perspective view of a switch-blade embodying my design. Fig. 2 is an end view of the same looking down upon Fig. 1.

As shown in the drawings, the leading or material feature of my design consists of a flat blade of metal 1, having the upper or outer end thereof cut inwardly from the edges,

as shown at 6 6, and the partly-cut-away portion 4 of the end of said blade bent into cylindrical form, leaving only the open slot 7 between the approaching edges of said cut-away portion 4. The inner surface of the cylindrical section so formed is provided with a helical groove 5, forming a screw-thread. 25 One edge of the blade is beveled, as shown at 3, and the other end of said blade is provided with a circular perforation 2.

It is apparent that this design is also applicable to knife-blades for other purposes. 35

Having therefore described my invention, what I claim as new, and desire to protect by Letters Patent, is—

The design for a knife-switch blade as herein shown and described. 40

In testimony whereof I affix my signature in presence of two witnesses.

GEORGE CHRISTOPHER HERZ.
